UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

THREAD-CONTROLLING MECHANISM.

1,416,697.

Specification of Letters Patent. Patented May 23, 1922.

Application filed May 31, 1919. Serial No. 301,052.

To all whom it may concern:

Be it known that I, ALBERT H. DE VOE, a citizen of the United States, residing at Westfield, in the county of Union and State 5 of New Jersey, have invented certain new and useful Improvements in Thread-Controlling Mechanism, of which the following is a specification, reference being had thereto in the accompanying drawings.

10 This invention relates to sewing machines and particularly to mechanism employed therewith for controlling the needle thread during each cycle of stitch-forming operations.

15 It aims to provide a new and improved mechanism which combines simplicity of construction with a nice capacity for controlling thread.

More specifically it aims to provide a 20 mechanism which will take up thread during the first and last portions of the needle's descent in order to prevent slack forming under the point of the descending needle and in order to assist the needle in drawing 25 up the previously shed needle-loop at the lower end of its downward movement.

It further aims to provide a mechanism 30 which will finally set the stitch during the ascent of the needle as it reaches its upper limit of movement and to set the stitch with a gradual pull or strain thereon in a manner not likely to cause the thread to break.

It also aims to provide a light and easy 35 running mechanism for controlling the needle thread capable of operation at a high rate of speed.

These are the objects of my invention and other objects thereof will appear in the following detailed description of the accompanying drawings in which Fig. 1 represents 40 a side elevation of a double thread chain-stitch machine to which the invention has been applied. Fig. 2 represents in full size the take-up for the needle thread showing the same on the head of the machine 45 which is sectioned vertically and broken away to better expose the mechanism to view. Fig. 3 is a transverse vertical section through the head of the machine showing 50 the relative arrangement of the parts and Fig. 4 is a detailed view showing in perspective the shape of the thread engaging or contacting portion of the take-up mechanism.

In the illustrated embodiment of the invention the stitch-forming instrumentalities proper comprise a pair of diagonally disposed needles 11 and pair of loopers 12. The needles 11 are secured as usual in a needle-clamp 13 having thread guiding fingers 14 for the respective needle threads, the clamp being fixed to the lower end of a needle-bar 15 pivotally connected by the pin 16 to a link 17 which in turn is pinned as indicated at 18 to a vibratory lever 19 55 fulcrumed on a pin 20 located centrally in the overhanging bracket-arm 21 and driven through the pitman 22 from a crank 23 on the main-shaft 24 of the machine.

The loopers 12 may be of any suitable 70 type and are in the illustrated embodiment of the invention of the thread-carrying type adapted to form a two thread chain-stitch. They may be supported and actuated in any suitable well known way and detailed description thereof is deemed unnecessary.

As more fully disclosed in my pending application Serial No. 149,719, filed Feb. 20, 1917, the overhanging arm 21 is grooved longitudinally on its face as indicated by 80 the numeral 25 and nearly covered by a plate 26 which defines with the groove a concealed thread passage for the needle-thread extending from the constant supply tension devices 27 to a point adjacent the 85 depending head 28 at the free end of the overhanging arm. Inner and outer cover plates 29 and 30 respectively are located at the junction of the head and overhanging arm in spaced relation to permit the passage 90 of the needle thread therebetween and the outer of these plates has a depending portion 31 which is inset in the head 28 and covers a channel 32 therein through which the thread passes freely down to the thread-guiding fingers 14 and thence to the needles 11. The plates 29 and 30 are also provided with arcuate openings 33 for a part 95 of the take-up mechanism.

The needle-thread controlling mechanism 100 comprises a stationary thread-guide 34 disposed internally of the concealed thread passage, a movable thread-guide or finger 35 which is secured by a screw 36 to the vibratory needle-lever 19 and which projects across the space between plates 29 and 30 through the slots 33, and a take-up whose active thread contacting portion is of the 105

form and construction indicated clearly in perspective in Fig. 4 and designated generally by the numeral 37. The take-up plate 37 is adjustably secured by the screw and 5 slot connection indicated at 38 to a lever 39 which is fulcrumed to a fixed part of the frame as indicated at 40 and which is actuated by a link 41 pinned at 42 to the vibratory needle-lever 19. The plate 37 or take-up proper is provided with a notch 43 at one 10 end and a groove 44 at its other end and with a lug 45 intermediate its ends which prevent the needle-thread slipping laterally off the plate. As indicated in Fig. 1 the 15 cover-plates 29 and 30 are cut away to form the registering crescent shaped openings indicated at 46, Fig. 1 only, affording clearance for the take-up proper or plate 37.

In Fig. 2 of the drawings the extremes of 20 movement of a single needle-eye are indicated by the numerals 1 to 5 and intermediate positions by the numerals 2, 3 and 4. Corresponding positions of the movable thread-guide 35 are indicated by the numerals 1° to 5° respectively and corresponding 25 positions of the opposite ends of the take-up plate 37 are likewise indicated by the numerals 1' to 5' inclusive and 1" to 5" inclusive.

30 The respective needles and loopers co-operate to form a two-thread chain-stitch in a manner well known the looper entering a loop of thread thrown out by the needle as it begins to ascend and holding the same until 35 the needle in its succeeding descent enters the triangle formed by the looper-thread extending from the eye of the looper to the preceding needle puncture, the needle-loop upon the looper, and the blade of the looper 40 itself, after which the needle-loop upon the looper is shed and drawn up by the further descent of the needle to the lower limit of its movement.

The desideratum in needle-thread controlling mechanism of the chain stitch type has 45 long been recognized to be a take-up which will draw or endeavor to draw thread back through the eye of the needle during the first and last portions of its descent from its 50 highest to its lowest position and which will at the same time set the stitch that has just been formed on the immediately following ascent of the needle to its highest position. The component parts of the thread-controlling mechanism which have been previously 55 described in detail are so organized and arranged in reference to the needle and looper that the desideratum is realized. As the needle descends from its upper limit of 60 movement the thread guide or finger 35 descends at substantially the same rate as the needle-eye, if anything being a little slower. The needle thread which extends from the fixed eye 34 over the left hand end of the 65 take-up 37 and across the thread-engaging

member 35 and thence passes downwardly to the needles, is not given up to the needle at first as fast as is required and consequently thread is drawn backwardly through the eye of the needle. This results from the 70 retarding action of the left hand end of the take-up plate 37 which, as apparent from an examination of Fig. 2, moves the slight distance between 1' and 2' while the thread engaging member 35 is moved from 1° to 2°. 75

As the needle continues in its descent the same end of the take-up 37 accelerates but its acceleration has no pronounced effect upon the thread until the point of the needle enters or is about to enter the work. At 80 about the time the needle loop is shed by the looper the right hand end of the take-up plate 37, which has been moving in a circle upwardly, becomes effective upon the needle-thread between the stationary thread-guide 85 34 and the movable thread-guide 35 to materially increase the take-up action on the thread. In the subsequent descent of the needle from about the time the needle-loop is shed until the needle reaches its lower 90 limit of movement this right hand end of the take-up 37 continues to pull upon the needle-thread extending from the supply to the needle and thereby assists the needle-eye in drawing the previously shed needle-loop up to the work. 95

In the ascent of the needle from its lower to its upper limit of movement the take-up 37 first slackens up on the thread leading to the needle and allows the latter to throw out 100 an abundantly large loop for the entrance of the looper and after the looper has entered the needle loop the thread engaging member 35 tends to tighten the needle-loop upon the looper. But the pulling action of 105 the thread engaging member 35 upon the needle-loop around the looper is gradual because of the modifying giving up action of the then descending right hand end of the take-up. As the needle continues to rise the left hand end of the take-up becomes more effective and in cooperation with the thread engaging finger 35 the left hand end of the take-up 37 insures a very gradual setting of 110 the stitch which is of course not completed 115 until the needle reaches its upper limit of movement.

From observations taken directly from a machine to which the invention has been applied it has been noted that there is a pulling off of needle-thread from the supply during the last portion of both the needle's descent and ascent. 120

While the thread controlling mechanism of the present invention may be used with the constant tension devices 27 only interposed between it and the source of supply, it is preferable for certain classes of work to employ an intermittent thread gripping device or nipper which is indicated on the 125 130

drawings by the numeral 47 and it is timed to grip the thread when the needle has almost reached its lower limit of movement in its descent. The nipper releases its grip upon the thread about the time the looper enters the needle-loop and during the ascent of the needle. This nipper may be of any suitable form and may be operated as more fully disclosed in my prior Patent No. 10 1,273,157, July 23, 1918.

Having thus set forth the nature of the invention, what I claim herein is—

1. In a sewing machine, in combination, stitch-forming mechanism including a needle, a looper, and thread-controlling mechanism including a stationary thread-guide and a movable thread-guide spaced from the first thread-guide, a thread-governing member having spaced thread-engaging portions both of which are located intermediate said guides, and means for moving said member relative to said guides to draw thread back through the eye of the needle during the first part of its descent and before its point reaches the work, and for moving said member relative to said thread-guides to assist the needle in drawing up the previous needle-loop after it has been shed by the looper and during the last part of the downward movement of the needle.

2. In a sewing machine having stitch-forming mechanism including a needle and a looper, in combination, thread-controlling mechanism including a stationary thread-guide, a second thread-guide movable in unison with the needle, a member having spaced thread-engaging portions intermediate said thread-guides, and means for oscillating said member during each stitch-forming cycle of operations and compelling it in cooperation with said second movable thread-guide to pull upon the needle-thread during the first and last portions of the needle's descent.

3. A thread-controlling mechanism for sewing machines having a needle comprising a stationary thread-guide, a movable thread-guide, a member mounted on a stationarily located pivot and arranged to operate upon the thread extending between said thread-guides, and means for moving said pivoted member in a circular path at a variable angular velocity whereby in cooperation with the movable thread-guide a change in the pulling action upon the thread is effected gradually during the first and last portions of the needle's descent.

4. In a sewing machine having stitch-forming mechanism including a needle and a looper, and in combination therewith, spaced thread-guides and an intermediate thread-governing member movable about a fixed pivot and having its opposite extremities arranged to alternately exert a dominating action upon the thread extending between said thread-guides by bending the thread in

the same direction during each stitch-forming cycle of operations, and means for moving said member.

5. In a chain-stitch sewing machine having stitch-forming mechanism including a needle and looper and vibratory lever for moving said needle, and in combination therewith, thread-controlling mechanism comprising a movable thread-guide and a stationary guide spaced therefrom a circularly 75 movable member comprising spaced thread-engaging portions one of which is arranged to contact with the thread extending between said thread-guides throughout each stitch-forming cycle of operations and the other 80 only during the latter part of the down stroke and first part of the up stroke of the needle, and means for moving said member including a link connected at its opposite ends to said member and said vibratory lever, respectively.

6. A thread-controlling mechanism for chain-stitch sewing machines having a needle and looper comprising relatively movable and spaced thread-guides and an intermediate 90 thread-governing member mounted on a stationarily located pivot and having a flat and relatively long thread-engaging portion, and means for moving said member arcuately and its ends oppositely with respect to the 95 direction in which the needle moves, whereby pull is exerted upon the needle-thread during the first and last portions of its descent.

7. In a sewing machine having stitch-forming mechanism including a needle, a 100 bracket arm in which said needle is mounted to reciprocate, and means for reciprocating said needle, in combination, thread-controlling mechanism including spaced thread-guides one of which is mounted to move substantially in unison with the needle and a 105 thread-governing member pivoted on the bracket arm between said guides and comprising spaced thread-engaging portions, and a link pivoted to the needle-operating 110 means and said member to oscillate the same about its pivot.

8. In a sewing machine having stitch-forming mechanism including a reciprocating needle, a thread-controlling mechanism 115 including spaced thread-guides, a thread-engaging member intermediate said guides having spaced thread-engaging portions, said member being so constructed and arranged that during the first part of the down stroke of the needle one of said portions only engages the thread and moves slowly to cause thread to slide through the eye of the needle and during the latter part of the down stroke of the needle the other portion 120 engages the thread to assist the needle in drawing up the previously shed needle-loop.

9. In a sewing machine having an arm, stitch-forming mechanism including a reciprocating needle, thread-controlling mech- 130

anism including a thread-guide mounted within the arm and adapted to move substantially in unison with the needle, a second thread-guide in said arm spaced from the first guide, and a thread-engaging member mounted within the confines of said arm between the guides and comprising spaced thread-engaging portions, and means for oscillating said member to vary its action on the thread.

10. In a sewing machine having an arm, stitch-forming mechanism including a reciprocating needle and thread-controlling

mechanism including spaced thread-guides located within said arm, a movable thread-engaging member located between said guides and wholly within the arm comprising spaced thread-engaging portions, and means for so moving said member that the effect of one of said portions on the thread decreases as the effect of the other increases and vice versa.

In testimony whereof, I have signed my name to this specification.

ALBERT H. DE VOE.
